(57) **CLAIM**

The ornamental design for a hunting, cutting and gutting tool, as shown and described.

DESCRIPTION

FIG. 1 is a first side elevation view of a first component of a hunting, cutting and gutting tool showing my new design;
FIG. 2 is a top plan view thereof;
FIG. 3 is an end view thereof;
FIG. 4 is an opposite end view thereof;
FIG. 5 is a bottom plan view thereof;
FIG. 6 is an opposite side view thereof;

FIG. 7 is a perspective view thereof.
FIG. 8 is a first side elevation view of a second component of a hunting, cutting and gutting tool showing my new design;
FIG. 9 is a top plan view thereof;
FIG. 10 is an end view thereof;
FIG. 11 is an opposite end view thereof;
FIG. 12 is a bottom plan view thereof;
FIG. 13 is an opposite side view thereof;
FIG. 14 is a perspective view thereof.
FIG. 15 is a first side elevation view of first and second components of a hunting, cutting and gutting tool in an assembled configuration showing my new design;
FIG. 16 is a top plan view thereof;
FIG. 17 is an end view thereof;
FIG. 18 is an opposite end view thereof;
FIG. 19 is a bottom plan view thereof;
FIG. 20 is an opposite side view thereof;
FIG. 21 is a perspective view thereof.
FIG. 22 is a first side elevation view of a modification to a first component of a hunting, cutting and gutting tool showing my new design;
FIG. 23 is a top plan view thereof;
FIG. 24 is an end view thereof;
FIG. 25 is an opposite end view thereof;
FIG. 26 is a bottom plan view thereof;
FIG. 27 is an opposite side view thereof;
FIG. 28 is a perspective view thereof.
FIG. 29 is a first side elevation view of a modification to a second component of a hunting, cutting and gutting tool showing my new design;
FIG. 30 is a top plan view thereof;
FIG. 31 is an end view thereof;
FIG. 32 is an opposite end view thereof;
FIG. 33 is a bottom plan view thereof;
FIG. 34 is an opposite side view thereof; and,
FIG. 35 is a perspective view thereof.
